United States Patent Office.

MARTIN LANDENBERGER, OF PHILADELPHIA, PENNSYLVANIA.

Design No. 4,271, dated August 2, 1870.

DESIGN FOR A KNITTED FABRIC.

The Schedule referred to in these Letters Patent and making part of the same

To all whom it may concern:

Be it known that I, MARTIN LANDENBERGER, of Philadelphia, in the county of Philadelphia and in the State of Pennsylvania, have invented a new and original Design for Knitted Fabric; and do hereby declare that the following is a full, clear, and exact description thereof, reference being had to the accompanying drawing and to the letters of reference marked thereon making a part of this specification.

The nature of my design is fully represented by the accompanying photographic illustration.

The tufted or piled portion of this fabric is made on a double-rib machine, provided with self-acting needles, and in the same manner as described in another application of mine now pending, and the plain portion is made by pressing the loops off the front bar altogether, at suitable intervals, and allowing them

to lap only on the back bar for a few courses, which makes the divisions or transverse untufted strips B, as shown in the drawing, such strips alternating with the tufted strips A.

By this means the fabric is rendered useful for a variety of purposes, such as, for instance, shawls, hoods, children's muff and tibbit, &c.

It may be made of any color desired.

What I claim is—

The design for knitted fabric, as shown and described.

In testimony that I claim the foregoing, I have hereunto set my hand this 7th day of July, 1870.

MARTIN LANDENBERGER.
